UNITED STATES PATENT OFFICE.

OSCAR LARSON, OF STOWE, VERMONT.

CATTLE-STANCHION.

1,171,446.

Specification of Letters Patent. Patented Feb. 15, 1916.

Application filed July 14, 1915. Serial No. 39,762.

To all whom it may concern:

Be it known that I, OSCAR LARSON, a citizen of the United States, residing at Stowe, in the county of Lamoille and State of Vermont, have invented certain new and useful Improvements in Cattle-Stanchions, of which the following is a specification.

This invention relates to improvements in cattle stanchions and its object is to provide means for releasing the movable stanchion bars simultaneously; means are also provided whereby one set of the movable bars may be individually released.

With the foregoing and other objects in view the invention consists in the combination and arrangements of parts to be herein-after fully described in the following specification, pointed out in the claims and illustrated in the accompanying drawings which form a part of said specification and in which—

Figure 1 is a front elevation. Fig. 2 is a detail view partly in section. Fig. 3 is a plan of Fig. 2. Fig. 4 is a section taken on line 4—4 of Fig. 1.

Like reference characters indicate corresponding parts throughout the several views.

The reference numeral 1 designates a building in which my stanchion may be housed and the stanchion comprises essentially a sliding rod 2 that extends through one wall of the building and is provided with handle 3; said rod being further supported in the angular bracket 4 and provided with the stop pin 5 which prevents its withdrawal from said bracket, and with the lug 6 to which one end of the return spring 7 is secured, the other end of said spring being secured to the building 1. Above each stall in the building a bell-crank 8 is arranged in a bracket 9, one end of said bell-crank being secured to the pull rod 2 and the other end being of hollow formation to permit its engagement with one end of the bolt 10 which bolt is movably supported thereby. The bolt 10 is formed with an angular lug 11 and between the same and the adjacent end of the bell-crank the eye-bolt 12 is carried, which bolt extends through the beam 13 and into a metal casing 14 which is secured to said beam. The said casing 14 is partly of curved tubular formation and this portion supports the movable retaining rods 15, 15 which extend beyond the ends of said casing 14 and that

are provided with the lugs 16 between which the stanchion bars 17 are terminally carried upon said rods; said stanchion bars being pivotally connected at their lower ends. 60 The inner ends of the rod 15 are apertured as at 18 to permit their releasable engagement by the angle pieces 19, 19 terminally carried by the eye-bolt 12 and said inner rod ends are engaged by the expansion 65 springs 20, the adjacent ends of which abut the collar 21 arranged within the casing 14 and apertured to admit the said eye-bolt 12. The normal position of the stanchion bars is illustrated in full lines in Fig. 1 and released or inoperative position in dotted lines 70 in that figure.

To move the stanchion bars from normal to released position the operator pulls upon the handle 3 of the pull rod causing that rod 75 to raise the free end of the bell-cranks in the several stalls simultaneously, thus withdrawing the several eye-bolts together with the sets of angle pieces 19, thus freeing the retaining rods 15, which are then expelled by 80 the expansion springs 20.

The device may be again placed in normal position by re-inserting the retaining rods, while the pull rod is in extended position, and then releasing that rod so that its spring 85 7 may return it together with the eye-bolts and their angle pieces.

To release one set of stanchion bars at a time the operator manually withdraws one bolt 10 from engagement with one bell-crank and then manually raises the eye-bolt with the result previously described as to the pair of stanchion bars associated with the eye-bolt.

What is claimed is:—

1. The combination with a pull rod, of bell-cranks, bolts terminally carried by said bell-cranks, eye-bolts carried by said first named bolts, tubular casings adapted to receive one end of said eye-bolts, retaining rods slidably arranged in said casings, stanchion bars terminally engaged by said retaining rods and pivotally connected at their lower ends, releasable connection between said retaining rods and said eye-bolts 100 and expansion springs within said casings in engagement with said retaining rods. 105

2. The combination with a pull rod, of bell cranks, bolts releasably carried by said bell cranks, eye-bolts carried by said first named bolts, tubular casings receiving the ends of said eye-bolts, collars within said 110

casings receiving the ends of said eye-bolts, retaining rods formed with terminal apertures movably arranged in said tubular casings, expansion springs connecting said retaining rods and the said collars, angle pieces normally connecting said eye-bolts and the apertured ends of said retaining rods whereby they are releasably retained in adjusted relation and stanchion bars termi-

nally engaged by said retaining rods and pivotally connected at their lower ends.

In testimony that the foregoing is my own I have hereto affixed my signature in the presence of two subscribing witnesses.

OSCAR LARSON.
